SCREW

Joseph F. Fleg, La Grange, Ill., assignor to
United Screw and Bolt Corporation, Chicago,
Ill., a corporation of Ohio

Application October 8, 1937, Serial No. 167,893

11 Claims. (Cl. 85—45)

This invention relates in general to screws and particularly to certain structural features which are advantageous in the use of the screws. While the invention is herein illustrated as embodied in a machine screw, it should be appreciated that the principles of the invention are equally applicable to wood screws, set screws, and, in fact, to screws of any kind whether hardened or not and whether intended to be driven into place with a hand operated screw driver or a power driven tool.

In my prior Patent No. 1,894,034, issued January 10, 1933, I disclosed a screw possessing certain advantages therein set forth over ordinary slotted head screws commonly in use. My present invention is an improvement upon the structure disclosed in said patent and embodies not only all of the advantageous features of the screw of that patent but also additional advantageous features which are highly desirable in many types of screws and for many purposes.

A screw of the character to which this invention relates has a recess or socket adapted for the reception of a tool in the form of a screw driver by which the screw is rotated and thereby driven into place. The socket centers the tool with respect to the screw and prevents the tool from slipping out of place as it frequently does with ordinary slotted head screws. Screws of the character with which my invention is concerned are very commonly driven into place with a power operated screw driver so constructed that when the end of the screw driver blade is pressed against the end of the screw a clutch is thrown in connecting the blade with the motor so that the blade immediately begins to rotate. Often the rotation of the blade is begun before its end has really entered the socket of the screw, and in such instances where the end of the blade is resting against the surrounding walls of the socket when rotation of the blade is started, the blade is as apt to slip laterally off from the screw as it is to slip inwardly into the socket.

One of the purposes of my present invention is to provide a screw which will facilitate the entrance of the tool blade into the socket, particularly when rotation of the blade is initiated.

Another purpose of the invention is to provide a screw driver blade which in conjunction with my improved screw head will further facilitate and insure the entrance of the blade into the screw head socket.

In modern practice screws are frequently employed in locations where it is very difficult to place and start them, particularly screws of the

thread forming machine screw type having a blunt entering end. Not infrequently, the location where the screw is to be driven is so inaccessible that the mechanic or user is unable to hold the screw in position with one hand while he manipulates the driving tool with the other. If, however, the screw were attached to and carried by the end of the tool, the screw could be easily guided and started.

Another and very important feature of my present invention is the provision of a screw so constructed that it may be very readily and securely attached to the screw driver blade so that it may be positioned and started by merely guiding the driving tool and without otherwise positioning or guiding the screw.

Other objects and many of the inherent features of my present invention will be readily appreciated as the same becomes better understood by reference to the following description when considered in connection with the accompanying drawing.

Referring to the drawing,

Fig. 1 is a plan view of my novel screw showing in cross section a screw driver blade in driving position in the socket of the head;

Fig. 2 is a similar view showing the screw driver blade in a position with respect to the screw in which the screw is frictionally locked to the blade;

Fig. 3 is a sectional view on the line 3—3 of Fig. 1 but showing the screw driver blade in full lines as withdrawn from the socket and in dotted lines as entering the socket; and

Fig. 4 is a sectional view on the line 4—4 of Fig. 2 showing the screw driver blade withdrawn from the socket and with its flat face presented to view.

Referring now to the drawing more in detail, reference character 5 indicates generally the body or shank of a screw threaded, as shown, and provided with a head 6. The body may be either of the machine screw type, as illustrated, or of the wood screw type and may be provided with threads of any suitable character. Likewise, the head 6 may be either of the flat type illustrated, or of the round or any other preferred type, as my invention is equally applicable to screws of various types including any preferred type of headless screw or a screw provided with a head.

In the embodiment shown, the head of the screw is provided with an axially disposed recess or socket, indicated generally by reference character 7 which, if preferred, may be of uniform

depth but preferably is of maximum depth at its center, as indicated by reference character 8. The socket is provided with oppositely disposed abutments or teeth 9 each providing an abutment face 11 in position to be engaged by the flat face of a tool such for instance as a screw driver blade 12 positioned diametrically in the socket and rotated in a clockwise direction viewing Figs. 1 and 2 into the position shown in Fig. 1 in which further rotation of the blade will rotate the screw for driving purposes. In this respect, the abutment teeth 9 are similar to the corresponding structure of my prior patent to which reference has been made.

15 For the purpose of providing a frictional attachment of the screw to the tool blade in order that the screw may be carried by the blade and thereby positioned for driving in inaccessible locations, the circumferential walls of the socket 1 are formed eccentric to the axis of the screw and socket. Viewing Figs. 1 and 2, it will be observed that the points 13 at the bases of the abutment faces 11 of the teeth 9 are more remote from the axis of the 25 socket than the points 14 at the bases of the other faces of the teeth. In other words, the circumferential walls 15 of the socket or at least a portion thereof between the teeth are formed on progressively shorter radii at progressively 30 increasing distances from the abutment faces 11 of the teeth. The diametral dimension of the socket is therefore greater on a diameter paralleling the faces 11 than it is on a diameter paralleling the other faces of the teeth.

35 The tool blade 12 is dimensioned so that it may be readily introduced and withdrawn from the socket when disposed diametrically of the slot in approximation to the position which it assumes in Fig. 1. From this figure it will be observed that considerable clearance is afforded between 40 the edges of the blade and the opposed walls of the socket. The tool may therefore be inserted and removed without resistance when disposed substantially in the position shown in Fig. 1.

45 Should it be desirable to attach the screw to the tool for placement and guiding purposes or otherwise, such attachment is readily effected by simply turning the tool blade in a reverse or counterclockwise direction in the socket from the position shown in Fig. 1 to that shown in Fig. 2 from which it will be observed that the edges of the blade have by this movement been brought into frictional holding engagement with and between the walls 15 so that the screw is securely 50 locked to the blade and may be carried thereby to any desired location which might otherwise be inaccessible for the starting of the screw. When the screw attached to the blade has been properly located, it may be driven in the usual manner, since a partial clockwise rotation of the tool blade will release the friction hold and bring it in abutting relation with the abutment surfaces 11 by which a driving rotation is delivered to the screw from the blade.

60 To facilitate the introduction of the tool blade into the socket, the exposed upper ends 16 of the teeth 9 are inclined downwardly and inwardly, as best shown in Fig. 4, instead of being parallel with the end face of the screw, as in my prior patent. These inclined tooth ends cause the tool blade to readily slide into the socket, thereby obviating many lateral slippages of the tool off the head of the screw which have heretofore occurred when an improperly placed tool began to rotate under power. These inclined surfaces

75 will obviously facilitate the introduction of a hand operated screw driver into the socket in the same manner that they do a power-operated tool.

An ordinary screw driver either hand or power operated or any flat type or suitably shaped 5 polygonal tool may be employed with screws embodying my invention, the only requirement being that the tool blade be sufficiently narrow to enter the socket in its largest diametral dimensions and sufficiently wide to engage the eccentric peripheral walls of the socket when reversely rotated if attachment of the screw to the blade is desired. An additional feature of my invention, however, which enables the introduction of the tool blade into the socket with even greater 15 facility resides in the design of a tool blade which, as illustrated in Figs. 3 and 4, is bluntly pointed instead of having a straight end perpendicular to the axis of the tool, as is customary. My novel blade has tapered end walls 17 and 18 20 terminating at their intersection in a sharp or blunt point 19, and preferably also the side faces are tapered, as indicated at 21 toward the point 18.

In the application of this tool to a screw of 25 my design, if the point 19 is positioned anywhere within the periphery of the socket, whether upon the exposed faces of the teeth 9 or elsewhere, endwise pressure exerted upon the tool will cause it to slide immediately toward the center of the 30 socket and become properly positioned therein. An exemplification of this action is illustrated by the dotted line position of the tool in Fig. 3.

It is believed that from the foregoing the principles of my invention and its attendant advantages will be understood and appreciated without further elaboration. The structural details, however, illustrated and described are obviously capable of considerable modification and variation without departing from the essence of the 40 invention as defined in the following claims.

I claim:

1. A screw having a socket provided with teeth spaced apart to accommodate between them a tool extending diametrically of the socket, said 45 teeth affording abutment surfaces for said tool through which rotary movements of the tool in one direction are imparted to the screw, the exposed ends of said teeth being inclined to facilitate entrance of the tool into said socket and the diametral distance between the circumferential walls of said socket being gradually diminished at points remote from said abutment surfaces to thereby produce a frictional engagement between said wall and the edges of the 50 tool upon the reverse rotation of said tool in said socket, whereby said screw is caused to be frictionally held by said tool.

2. A screw having a socket provided with oppositely disposed teeth providing abutment surfaces, the circumferential walls of said socket between said teeth being formed on radii of progressively diminishing lengths at progressively 55 remote points in a counter-clockwise direction viewed from the top from one cooperating pair of abutment surfaces to grip the edges of a tool of suitable width diametrically disposed in said socket upon rotation of said tool in the socket away from said cooperating pair of abutment surfaces of said teeth.

3. A screw having a tool receiving socket dimensioned to receive an elongated flat type tool diametrically positioned therein, said socket being provided with abutment surfaces disposed for engagement by said tool when rotated in one 70 75

direction and with inclined surfaces arranged to frictionally engage said tool when rotated in the opposite direction to thereby frictionally attach said screw to said tool.

5 4. The combination with a polygonal tool, of a screw having a head provided with a socket of a diametral dimension to receive said tool in one position, said socket being provided with an abutment positioned to be engaged by a flat face 10 of said tool when rotated in one direction whereby movement of said tool is imparted to said screw head, the circumferential walls of said socket being formed on progressively diminishing socket radii to provide a frictional engagement with the edges of said tool when rotated in a reverse direction.

5 5. The combination with an elongated flattened tool, of a screw having a socket dimensioned to freely receive said tool in diametral 20 position therein, said socket being shaped to present an abutment in the path of said tool when rotated in one direction from said position and to oppose by frictional resistance the rotation of the tool in the opposite direction 25 from said position whereby a frictional connection between said tool and said screw is established.

6. A screw having a tool receiving socket provided with abutment means for transmitting turning movements in one direction of a tool in said socket, and with friction means for frictionally locking said tool and screw together

upon turning movement of the tool in the opposite direction.

7. A screw provided with a tool receiving socket, opposite portions of the circumferential walls of said socket being eccentric to the longitudinal axis of the socket. 5

8. A screw provided with a tool receiving socket, a portion of the circumferential walls of said socket being disposed eccentrically with respect to the longitudinal axis of said socket. 10

9. A screw provided with a tool receiving socket, said socket being equipped with spaced apart abutment teeth and having circumferential walls between said teeth formed eccentrically with respect to the longitudinal axis of said 15 socket.

10. A screw provided with a tool receiving socket presenting abutment surfaces for engagement by a tool when said tool is rotated in one direction in said socket and presenting inclined 20 surfaces for frictional engagement by said tool when rotated in the opposite direction in said socket whereby said screw may be frictionally attached to said tool.

11. A screw having a tool receiving socket 25 shaped to provide a tool engaging surface formed on a curve eccentric to the longitudinal axis of the socket for frictionally locking the screw to a tool upon rotation of the tool in one direction relatively to the screw. 30
